UNITED STATES PATENT OFFICE.

NEAL W. DORMAN AND MEREDITH R. HATCH, OF TOLEDO, OHIO, ASSIGNORS TO THE TOLEDO MACHINE AND TOOL COMPANY, OF TOLEDO, OHIO, A CORPORATION OF OHIO.

TOGGLE PRESS.

Application filed October 24, 1925. Serial No. 64,567.

This invention relates to drawing on toggle presses and particularly to the mechanism employed for communicating the requisite movements and dwell to the blank holder from the customary crank shaft or other operating means.

An object of our invention is to produce an improved mechanism of the above class which will permit a prolonged dwell or rest of the blank holder in work-blank holding position during the work drawing or forming movements of the press plunger, thus enabling the performance of deep drawing or stamping, and materially enhancing the practicability and commercial value of presses of this character.

Another object of the invention is to produce a simple and improved press having the unique features of construction, operation and arrangement hereinafter more fully described.

The invention is shown by way of illustration in the accompanying drawings, in which,

Fig. 1 is a front elevation of a press embodying the invention with the lower portion broken away and with the blank holder and die carrying plunger in their uppermost position; Fig. 2 is a vertical section on the line 2—2 in Fig. 1; Fig. 3 is a view similar to Fig. 2 showing both the blank-holder and plunger in their lowermost positions; Fig. 4 is a transverse section on the line 4—4 in Fig. 2 showing the sliding block and guideway; and Fig. 5 is a diagram indicating the length of dwell of the blank holder relative to the movement of the plunger.

The illustrated embodiment of the invention comprises a pair of uprights 1 and 2 having a support 3 therebetween for the female or matrix die and vertically reciprocable between and guided by the uprights 1 and 2 is a blank holder 4 which is adapted to be moved into position to engage the work and hold the same during the pressing or forming operation of the male die (not shown) which is carried by a plunger 5 reciprocating in and guided by the blank or work-holder 4, as is well understood in the art.

The mechanism shown for reciprocating the die-carrying plunger 5 comprises a crank-shaft 6 which has bearings at its opposite

end portions in the uprights 1 and 2, respectively, and fixed to each or either end of the crank-shaft is a gear 7 driven by a pinion 8 on a drive-shaft 8^a. Although it may be desirable to employ a gear 7 at each end of the crank shaft 6 to obtain a more balanced action, it is to be understood that a single gear may be advantageously employed if desired.

The die-carrying plunger 5 is operated from the crank shaft 6 by a pitman 9, which may be formed in two sections connected together by a screw 10^a rotatable in one section and in threaded engagement with the other section. Suitable mechanism is employed for turning the bolt 10^a so that length adjustment of the pitman 9 may be effected thereby moving the plunger 5 closer to or farther away from the work, it being observed that the lower end of the arm 9 is pivoted to the plunger.

Extending across the upper portion of the frame, and bearing at its opposite ends in the uprights 1 and 2 is a rock-shaft 10 having a crank 11 fixed to each end. The cranks 11 are connected to offset pins 12 on the crank-shaft 6 or gears 7 by means of links 13 so that rotation of the crank-shaft 6 through the above connections imparts a rocking action to the shaft 10.

Fixed to the rock-shaft 10 centrally thereof is a triangular-shaped lever member providing lever arms 14 and 15, the triangular-shaped lever member having equal sides with an apex connected securely to the shaft 10. Pivoted at one end to the arm 15 is a link 16, which is pivotally connected at its opposite end to a slide 17 movable in a guide 18. The guide 18 may constitute a part of the frame or may be connected thereto, and as shown, is disposed in angular position with the upper end inclined inwardly toward the vertical plane of the rock-shaft 10 and with the lower end extending away from said plane. In the form shown, the guide 18 is inclined about 45° from a vertical plane 100 pressing through the rock shaft 10. It is to be understood that the position of this guide may be varied according to the operation desired.

Pivoted at one end to the arm 14 is a link 19, which is pivotally connected at its opposite end to a slide-block 20 movable in a guide 21. In this instance, the guide 21 is

positioned on the opposite side of the rock-shaft to the guide 18 and is inclined at an angle of equal to angle of guide 18. It will be noted that the arm 19 is slightly curved 5 to give clearance to the arm 15 when the rock shaft 10 is moved in a clockwise direction, as indicated in Fig. 2, while the guide 18 is provided with an opening thru which the link 16 may extend when in the position 10 (Fig. 2).

In the operation of the mechanism so far described, rocking movement is imparted to the rock-shaft 10 from the crank shaft 6 by means of the links 13, and by movement 15 of the rock-shaft 10 in a clockwise direction both the slide-blocks 17 and 20 are drawn upwardly in the guides 18 and 21 respectively. When the rock shaft 10 reverses its movements or turns in a counter clockwise 20 direction, both slide-blocks 17 and 20 move downwardly and outwardly in their respective guides. In this manner it will be seen that a balanced action is obtained thru the positioning of the mechanism on opposite 25 sides of the rock-shaft which is disposed centrally of the machine.

A pair of arms 22^a and 23^a project from the center of the respective shafts 22 and 23, and these are respectively connected to the 30 lower ends of the slides 17 and 20 by links 24 and 24^a. Each rock-shaft 22, 23 has a pair of arms 25 and 25^a projecting therefrom at each side of the respective arms 22^a and 23^a at approximately right angles thereto 35 and these are connected by links 27 to members 28.

From the above description it will be seen that clockwise movement of the rock-shaft 10 operates to raise or move the slides 17 and 40 20 upwardly, thereby tending to rotate the rock-shaft 22 in a counter-clockwise direction and the rock-shaft 23 in a clockwise direction. This opposite movement of the shafts 22 and 23 exerts, through the arms 25 and 25^a respectively, an upward pull on the 45 links 27, thereby raising the blank-holder 4 away from the work. It will also be apparent that movement of the rock-shaft 10 in a counter-clockwise direction operates 50 through the connections described to rotate the rock-shaft 22 in a clockwise direction and the rock-shaft 23 in a counter-clockwise direction, thus operating to move the blank-holder downwardly or outwardly against the work to hold the latter in place as indicated 55 in Fig. 3.

It is desirable that the blank-holder 4 be moved into holding engagement with the work before the plunger 5 engages the work, 60 and to maintain its blank-holding position until the plunger has been retracted. As indicated diagrammatically in Fig. 5, the line *a* indicates the operation of the blank-holder and the line *b* indicates the operation of the plunger. It will be seen from this diagram

that the blank-holder 4 is moved into work hiding position almost immediately after the plunger 5 begins its downward movement and does not release the work until the plunger has traversed a distance in its re- 70 tracting movement.

It is apparent that with the present blank holder operating means the blank holder 4, crank shaft 6 and rock shaft 10 are located in a common vertical plane which is parallel 75 to the shafts; that the pair of rock shafts 22 and 23 are disposed at opposite sides of and at equal distances from said plane, so that at all times the parts are in perfect balanced relation, which is an important feature in 80 presses of this character, in order to cause a smooth running and to prevent vibration and unnecessary strains in the machine. Upon a rocking of the shaft 10 the thrust and pulling forces communicated thereby to the rock 85 shafts 22 and 23 are equal at all times and with respect to the center of the machine. While the machine is preferably provided with two side gears 7, from which power is 90 communicated equally to each end of the rock shaft 10, it is apparent that only one of such gears may be employed and that the shaft 10 may be driven from only one end, as desired. It is preferable, however, for a perfect balanced action of the press and in order to prevent torsional strain on the shaft 10 that the 95 arrangement be as indicated.

While the form of mechanism here shown and described is admirably adapted to fulfil the objections primarily stated, it is to be 100 understood that it is not intended to confine the invention to the one form of embodiment herein disclosed, and it is susceptible of embodiment in various forms, all coming within the scope of the appended claims.

What we claim as new and desire to secure by Letters Patent, is:

1. A press comprising a crank shaft, a blankholder, and means for operating said blank-holder, said means comprising rocking parts at each side of the press turning on axes parallel to the crank shaft, toggles between said rocking parts and said blankholder, an oscillatory rocking part above and approximately coextensive with said crank shaft, connections between said first rocking parts and said oscillatory rocking part for transmitting movements from latter to the former, and an operative connection between said crank shaft and oscillatory rocking part.

2. A press comprising a crank shaft, a blankholder, and means for operating said blank-holder, said means comprising rocking parts at each side of the press turning on axes parallel to the crank shaft, toggles between said rocking parts and said blankholder, a second rocking part nearer the middle of the press and turning on an axis parallel to the crank shaft, said second rock- 125 130

ing part being approximately coextensive with said crank shaft, connections between intermediate portions of said first and second rocking parts for transmitting movements from the latter to the former, and an operative connection between said crank shaft and second rocking part.

3. A press comprising a crank shaft, a blank-holder, and means for operating said blank-holder, said means comprising rocking parts at each side of the press turning on axes parallel to the crank shaft, toggles between said rocking parts and blank-holder, a second rocking part nearer the middle of the press, disposed above and turning on an axis parallel to said first rocking parts and crank shaft, connections between intermediate portions of said first and second rocking parts for transmitting movement from the latter to the former, and operative driving connections between opposite end portions of said crank shaft and said second rocking part.

4. In a toggle press, a blank holder, a single rock shaft disposed centrally above the blank-holder, a pair of rock shafts disposed below and at opposite sides of the single rock shaft, means for rocking the single rock shaft, means connecting the single rock shaft to each of said other rock shafts to impart predetermined rocking movements to the latter from the former, said means including reciprocatory movable members operating in inclined intersecting planes, and means connecting said lower rock shafts to the blank holder for imparting reciprocatory movements to the latter from rocking movements of the former.

5. In a toggle press, a frame, a plunger-operating crank shaft in said frame, a rock shaft above said crank shaft, an operative connection between said shafts, and blank-holding mechanism operatively associated with said rock-shaft and including arms fixed to said rock-shaft, angularly disposed guides on opposite sides of said shaft, blocks slideable in said guides, and a link connecting each pair of blocks and arms respectively whereby rocking movements of said rock shaft in one direction moves said blocks inwardly in said guides and movement in the opposite direction moves said blocks outwardly.

6. In a toggle press, a frame, a plunger-operating crank-shaft in said frame, a rock-shaft operatively connected to said crank-shaft, guides on opposite sides of and below said rock-shaft and disposed centrally of the machine, said guides being inclined inwardly toward said rock-shaft, arms fixed to said rock-shaft and extending oppositely therefrom, links pivoted to said arms, respectively, blocks slideable in said guides and connected to said links, rock shafts in said frame extending approximately par-

allel to said first rock-shaft, arms fixed to said last rock-shaft and pivoted to said blocks, a blank-holder, and links connecting said arms to said blank-holder.

7. In a toggle press, a frame, a blank-holder mounted for reciprocatory movements in the frame, a rock-shaft mounted in the frame crosswise thereof, means for operating said shaft, guides on opposite sides of said shaft disposed below and with the upper ends thereof inclined inwardly toward said shaft, members slideable in said guides, links connected to said members respectively at one end and operatively connected to said shaft at the other end, rock-shafts extending crosswise of said frame below said guides, arms fixed to said last rock-shafts, links connecting said arms and slideable members, and operative connections between said last rock-shaft and blank-holder.

8. In a toggle press, a frame, a blank-holder mounted for reciprocatory movements in the frame, a rock shaft mounted in the frame crosswise thereof, means for operating said shaft and mechanism operatively connecting said shaft and blank-holder including guides disposed below and on opposite sides of said shaft with their inner ends inclined inwardly, members slideable in said guides, and links pivoted at one end to said members and operatively connected at their opposite ends to said shaft whereby a rocking movement of said shaft in one direction moves said members inwardly in said guides and movement in the opposite direction moves said members outwardly in said guides.

9. In a toggle press, a frame, a blank-holder mounted for vertical reciprocatory movements in said frame, a rock-shaft mounted in said frame crosswise thereof, means for operating said shaft, and operative connections between said shaft and blank-holder including angularly disposed guides, members movable in said guides, and means for connecting said members to said shaft whereby oscillatory movement of said shaft in one direction moves both members conjointly in one direction and movement of said shaft in the opposite direction moves both members in the opposite direction.

10. In a toggle press, a frame, a blank-holder mounted for vertical reciprocatory movements in said frame, a plunger-operating crank-shaft mounted in said frame crosswise thereof, a rock-shaft above and extending substantially parallel to said crank-shaft, an operative connection between said crank-shaft and rock-shaft, and mechanism for operatively connecting said rock-shaft to said blank-holder for imparting reciprocatory movements thereto, said mechanism including a pair of angularly disposed arms fixed to said rock-shaft, links pivoted re-

spectively to said arms, blocks pivoted to said links, angularly disposed guides for said blocks, rock shafts mounted in spaced relation in said frame, connections between 5 said last rock-shafts and said blocks, and connections between said last rock-shafts and said blocks, and connections between said last rock-shafts and blank-holder.

11. In a toggle press, a frame, a blank-holder mounted for vertical reciprocatory movements in said frame, a plunger-operating crank-shaft disposed centrally of said frame, a rock-shaft in said frame parallel to and disposed approximately in the vertical plane of said crank shaft, a connection between said crank shaft and rock shaft, a rock-shaft on each side of said crank-shaft in parallel relation thereto and intermediate 15 said first rock-shaft and crank shaft, guides 20 in said frame adjacent said last rock shafts and inclined toward said first rock-shaft, members slideable in said guides, link connections between said members and first rock-shaft, connections between said members 25 and said last rock-shafts whereby oscillation of said first rock-shaft turns said second rock-shafts in opposite directions, arms fixed to said second rock-shafts, and links connecting said arms and blank-holder. 30

12. In a toggle press, a frame, a blank-holder mounted for reciprocatory movements in said frame, a rock-shaft in said frame cross-wise thereof, means for operating 35 said rock shaft, a double lever fixed to said shaft, angularly disposed guides on

opposite sides of said lever, members movable in said guides, links connecting said members and lever whereby oscillatory movement of said rock-shaft in one direction moves both members inwardly said guides and movement thereof in the opposite direction moves both members outwardly in said guides, and mechanism for transmitting the movement of said members to said blank-holder thereby to lift the same when moved in one direction and lower the same when moved in the opposite direction. 45

13. In a toggle-press, a blank-holder, a pair of slide members operable in divergent planes, a stationary guide for each of said slide members, means for reciprocating the slide members in unison, and means connecting the slides to the blank-holder for imparting reciprocatory movements to the latter from the former. 50

14. In combination with the frame, a crank shaft and reciprocatory blank-holder of a drawing press, a rock shaft mounted midway of the frame and above the crank shaft and having arms projecting towards opposite sides of the frame, operative connections between each arm, and the blank-holder on the side of the frame towards which the respective arm projects, and driving connections from opposite ends of said crank shaft to said rock shaft. 60

In testimony whereof we have hereunto signed our names to this specification.

NEAL W. DORMAN.
MEREDITH R. HATCH.
